Specification for Design.

Patented Jan. 15, 1918.

Application filed December 23, 1916. Serial No. 138,681. Term of patent 14 years.

To all whom it may concern:

Be it known that I, ALBERT F. SEIBERLING, a citizen of the United States, and a resident of Jonesboro, in the county of Grant and State of Indiana, United States of America, have invented a new, original, and ornamental Design for Vehicle-Tires, of which the following is a specification, reference being had to the accompanying drawing, forming part thereof, and in which—

Figure 1 is a developed plan view of a

portion of a vehicle tire embodying my new design; and

Fig. 2 is a transverse section on the line 2—2, Fig. 1.

I claim:

The ornamental design for a vehicle tire, as shown.

ALBERT F. SEIBERLING.
